UNITED STATES PATENT OFFICE.

HENRY GRANT LUNDQUIST, OF SANFORD, FLORIDA.

MATCH-CASE.

1,084,456.

Specification of Letters Patent. Patented Jan. 13, 1914.

Application filed January 27, 1913. Serial No. 744,455.

To all whom it may concern:

Be it known that I, HENRY G. LUNDQUIST, a citizen of the United States, residing at Sanford, in the county of Orange and State of Florida, have invented certain new and useful Improvements in Match-Cases, of which the following is a specification, reference being had therein to the accompanying drawing.

10 This invention relates to pocket match boxes and has for its object the production of a plurality of door members carried at each corner thereof whereby access may be had to the interior of the box or case without regard to the corner which may be presented.

Another object of this invention is the production of a pocket match box or safe of the character described which is provided 20 with a comparatively smooth outer wearing surface.

With these and other objects in view, this invention consists of certain novel constructions, combinations and arrangements of 25 parts, as will be hereinafter fully described and claimed.

In the accompanying drawing:—Figure 1 is a side elevation of the match box case. Fig. 2 is a side elevation of the case showing 30 the doors in an open position. Fig. 3 is a central longitudinal section of the case. Fig. 4 is a section taken on the line 4—4 of Fig. 3. Fig. 5 is an enlarged sectional view of a portion of one of the doors illustrating the 35 spring latch member.

By referring to the accompanying drawing by numerals, it will be seen that this device consists of a body 1 which is provided with the arc-shaped opening 2 adjacent 40 which is formed the upstanding rim or sealing plate 3. This rim 3 is formed by positioning a portion of the body 1 adjacent the opening 2 out of alinement with the remainder of the body. Each rim or sealing plate 3 is provided at its outer edge or end 45 with inwardly extending feet 4' which engage the side walls of the body for assisting in holding the rim in its correct position. The opposite ends of the plates 3 engage the 50 abutments formed at the ends of the partition 8 as illustrated in Fig. 3. An opening of this character is formed at each corner of the case 1, and at each end of this case and between the openings thereof there is provided 55 a supporting plate 4 which carries the hinge members 5 to which the covers 6 are

pivotedly mounted. These covers 6 are adapted to fit over the rim 3 whereby when the lids are in the closed position as illustrated in Fig. 1, in this manner moisture will 60 be prevented from entering the casing while the side portions of the same will present an even wearing surface.

A central partition 8 is carried within the body 1 and extends longitudinally thereof. 65 This partition 8 carries at the end portion thereof and upon each side springs 9 which are held in position by means of rivets 10. These springs 9 are formed of flat spring metal and are provided with the bent portion 11 which extends so as to terminate in the angularly bent portion 12. The bent portion 11 rests upon the door adjacent the end 4 while the angularly bent portion 12 extends for a considerable distance upon the 70 interior of the door whereby the same is adapted to be sprung open by aid of the spring.

In order to hold the doors in a closed position, each door is provided with an aperture 80 13. The portion of the case adjacent the forward edge of the door is provided with a flat spring 14 which carries the integrally formed knob 15 and when the door is in a closed position, this knob 15 rests within the 85 aperture 13 for holding the door in the closed position. When it is desired to open any one of the doors, the knob 15 is pressed inwardly, at which time the pressure of the spring member 9 will cause the door to fly 90 open at which time the contents within the case may be easily removed since the arc-shape of the opening will allow the contents to extend so as to be easily gripped.

From the foregoing description, it will be 95 seen that when it is desired to remove the matches from the case, access may be had thereto at any corner which happens to present itself and will in this manner eliminate the trouble of finding the latch such as ordinarily used in a case which is provided with only one door.

Having thus described the invention, what is claimed as new, is:—

A match case comprising a body provided 105 with a central partition, said body provided with open corners, hinged doors secured to said body adjacent said central partition and adapted to normally close the open corners of said body, said body provided with sealing plates extending around the edge of said 110 corner openings for constituting a guide for

directing said doors to a closed position over the open corners of said body and also assisting in sealing said body along the edge of said doors for preventing the admission 5 of dampness into the interior of said body, flat springs secured to said partition upon each side thereof and extending longitudinally thereof for a portion of its length, said springs engaging the inner faces of said 10 doors for normally exerting an outward pressure thereon and extending between the side walls of said doors whereby the lateral twist of said springs will be resisted, said body extending beyond each side of said central partition for constituting abutments, the 15

inner ends of said sealing plates engaging said abutments, said abutments constituting means for assisting in holding said plates upon said body, and said plates provided at their opposite ends with inwardly bent feet, 20 said feet lying flat upon the side walls of said body and also assisting in holding said plates in position.

In testimony whereof I hereunto affix my signature in presence of two witnesses.

HENRY GRANT LUNDQUIST.
